UNITED STATES PATENT OFFICE.

WILLIAM N. GOLDHAMER, OF ST. LOUIS, MISSOURI.

COOKING STOVE AND RANGE.

1,127,229.

Specification of Letters Patent.

Patented Feb. 2, 1915.

Application filed August 5, 1912. Serial No. 713,351.

To all whom it may concern:

Be it known that I, WILLIAM N. GOLDHAMER, a citizen of the United States, residing at the city of St. Louis, State of Missouri, have invented certain new and useful Improvements in Cooking Stoves and Ranges, of which the following is a specification, reference being had to the accompanying drawings, forming a part hereof.

10 My invention relates generally to certain new and useful improvements in stoves and ranges used for cooking purposes, and more particularly in the structure or formation of the front walls and ovens thereof.

15 Heretofore in the manufacture of cooking stoves and ranges it has been the general practice, so far as I am aware, to form the front walls of such stoves and ranges from large sections of sheet metal and to attach thereto and on the outer face or surface

20 thereof the various door frames usually of cast metal, the sheet metal sections being cut away within the area of such frames to provide the corresponding openings; it has

25 further been the general practice to outwardly flange the outer or open end of the oven shell and fixedly attach such end thereof directly to the inner face or surface of, and support the same by, said sheet

30 metal sections. This practice, however, has been found objectionable, for the reason that the large sections of sheet metal do not have sufficient rigidity to properly hold the weight of the cast metal frames and oven

35 fixed thereon, thus permitting the front wall to more or less readily bend or buckle out of shape, and also for the reason that the use of such large sections of sheet metal alone not only adds considerable to the cost

40 of manufacture, but also results in the employment of extra labor and in a waste of a large amount of material.

It is the object of my invention to obviate such objectionable practice and to provide

45 a stove front which will not only have strength and rigidity and, at the same time, present a neat and attractive appearance, but which will also cost considerably less to manufacture or produce. To that end,

50 it may be briefly here stated, I propose to form the front walls of cooking stoves and ranges of one or more skeleton frames of cast metal and to close the openings therein, with the exception of the door openings,

55 with comparatively small sections or pieces of sheet metal. By such construction, I am

enabled to produce a stove or range front having great strength and rigidity and which is comparatively inexpensive in manufacture, for the reason that there is a great saving of labor, no waste of material, and only a minimum number of small sections or pieces of sheet metal are essential in the formation of the improved stove front. I also propose to form on the main frame of the front wall an inwardly projecting flange that is adapted to directly receive and firmly support the straight front edges of the oven-housing or shell, all flanging of the oven-housing at said edges being done away with.

With the above and other objects in view, my invention resides in certain novel features of construction, arrangement, and combination of parts, all as hereinafter fully described and afterward pointed out in the claims.

In the accompanying drawings—Figure 1 is a front elevational view of a stove or range embodying my invention; Fig. 2 is a horizontal sectional view thereof taken on the line 2—2 of Fig. 1; Fig. 3 is an elevational view looking against the inside of the members that form my improved stove front, one of said members being broken away; Fig. 4 is an enlarged detail sectional view taken on the line 4—4 of Fig. 1; and Fig. 5 is a perspective view of the oven-housing or shell, the forward end of which, in the finished stove or range, is attached directly to, and supported by, the stove or range front of my improved construction.

Referring by numerals to said drawings, which illustrate my invention in connection with a stove or range which is otherwise of ordinary construction, 1 designates the stove base, 2 the legs supporting said base, 3 the rear wall, 4—4 the side walls, and 5 the stove top, all of which parts are of ordinary, well-known construction.

100 The main portion A of the front wall of the stove as contemplated by my invention is formed in a single piece preferably by casting and comprises a bottom horizontally-disposed piece 6, vertically-disposed end-pieces 7 and 8, and a top horizontally-disposed piece 9. These pieces form a rectangular skeleton frame around the oven-door opening 10, the edges of said pieces adjacent said opening being recessed, as at 110 11 and 11^a, so as to accommodate the edges and hinges of an oven door (not shown).

Formed in the center of the bottom piece 6 is a horizontally-disposed preferably rectangular opening 12 normally closed by a door (not shown) and which opening permits ready access to the space within the stove-body beneath the oven. And formed in the bottom piece 6 to the sides of said opening 12, are somewhat elliptical openings 13-13 that are closed by means of small sheet metal plates 14-14, which latter are arranged on the inner face of piece 6 and fixedly secured thereto in any suitable manner, preferably by means of rivets or stove-bolts 14^a, the said member or frame A being mounted upon base 1 and firmly and securely fixed thereto in any suitable manner, preferably by means of stove-bolts or screws 6^a passing through the lower portion of piece 6, as shown particularly in Figs. 1 and 3.

Formed through the top piece 9 is an elongated horizontally-disposed opening 15, and applied to the inner face of said piece 9, and fixed thereto in any suitable manner, as by stove-bolts 16^b, so as to close said opening, is a narrow sheet metal plate, which may be imperforate, as shown and designated at 16 in Fig. 3, or perforated so as to provide openings adapted to receive gas-burners or pipes, as shown and designated at 16^a in Fig. 1.

Formed in the side piece 8 is one or more narrow vertically-disposed somewhat elliptical openings 8^a and applied on the inner face of, and fixedly attached in any suitable manner to, said piece 8 is a series of small sections of sheet metal 17, which close said openings 8^a.

Formed integrally with member A adjacent the outer edge of piece 8 and projecting inwardly or rearwardly therefrom is a vertically-disposed flange 18 that lies immediately inside and to which is suitably firmly attached the front edge of the corresponding end wall 4; and likewise formed integrally with member A adjacent the upper edge of piece 9 is an inwardly presented horizontally-disposed flange 18^a to which is suitably firmly attached the front portion 50 of stove-top 5.

Formed integrally with the pieces 6, 7, 8, and 9 of member A adjacent the edges of oven-door opening 10, are inwardly projecting flanges 19, which serve as points of direct attachment and support for the front edges of an oven-shell or housing B. This shell or housing, shown particularly in Fig. 5, is substantially rectangular in form and comprises preferably a top wall 20, a bottom wall 21, and side walls 22-22, the said walls being flanged outwardly at their rear edges, as at 20^a, and thereby adapted to be readily attached to the rear wall 3 of the stove-body. The edges of top-wall 20 of this oven B are flanged or bent downwardly

and overlap, and are adapted to be fastened to, the upper edges of the side walls 22-22, and likewise the lower edges of the side walls 22-22 are flanged or bent inwardly and overlap, and are adapted to be fastened to, the side edges of bottom wall 21. To accommodate these overlapped or thickened edges of the walls of the oven B, the corners of the frame formed by the flanges 19 are recessed, as at 19^a, the said oven B being adapted to neatly seat and be firmly supported at its forward end in and by, and secured to, the frame formed by said flanges 19.

Under ordinary circumstances or in stoves or ranges of ordinary length, the vertical piece 7 of member A may be comparatively narrow, as shown, but, where the stove is of extra length, this piece 7 may be materially widened and provided with openings the same as piece 8, if desired.

The skeleton frame C utilized in connection with the frame A in forming the stove-front is arranged in front of the fire-box and ash compartments of the stove and comprises vertically-disposed side pieces 23 and 24, horizontally-disposed top piece 25, horizontally-disposed bottom piece 26, and horizontally-disposed intermediate pieces 27, 28, and 29. This frame C is also formed in a single integral piece, preferably by casting, and the various parts named are so arranged and located as to readily combine with the frame A. The side piece 23 is integrally provided with a rearwardly extending vertically-disposed flange 30, to which is fixed the forward edge of the corresponding side wall 4, as shown particularly in Fig. 2, and the side piece 24, which is adapted to lie immediately beneath, and is suitably fixed, by stove-bolts or the like 24^a, to, the side piece 7 of frame A, is preferably undercut or recessed on its front face, so that, when in position, the outer faces of said members A and C will be substantially flush with each other. The space between the top piece 25 and intermediate piece 27 forms the usual fuel opening into the fire-box, and which opening is normally closed by a suitable door (not shown).

The space between the intermediate pieces 27 and 28 forms an opening in which is arranged a suitable grate-housing (not shown). The space between the intermediate pieces 28 and 29 is closed by a small section of sheet metal 28^a, the same being applied to the inner side of the frame C and fixed thereto in any suitable manner. The space between the piece 29 and bottom piece 26 forms an opening into the ash-box compartment beneath the fire-box and this opening is likewise normally closed by a suitable door (not shown).

It will be understood that the various doors herein referred to, and not shown in

the drawings, are of ordinary well-known construction and will preferably be hinged to frames A and C in any suitable manner.

The stove front illustrated in the accompanying drawings is particularly adapted for use in connection with a combination coal and gas stove or range, but it will be understood that the embodiment of my invention can be advantageously utilized in connection with all forms of coal or gas-heated cooking stoves or ranges and the like.

By my improved construction, a very strong, rigid, and durable stove front is produced, and by casting the frames or forming the same in a single piece and closing a number of the openings in the frame with small sections or pieces of sheet metal, the entire stove front can be manufactured at comparatively little cost. If desired, the small sections of sheet metal used on the frame may be enameled and especially in such case the stove front presents a neat, finished, and pleasing appearance, inasmuch as the enameled plates form a series of panels between the various doors of the frame.

It will be readily understood that minor changes in the size, form, arrangement, construction, and combination of the various parts of my invention may be made and substituted for those herein shown and described without departing from the nature and principle of my invention.

Having thus described my invention, what I claim and desire to secure by Letters Patent is:

1. The stove or range wall herein described, the same including a relatively heavy, thick, cast-metal rigid plate, said plate being transversely provided within its area with a plurality of separate openings,

a plurality of separate independent relatively thin sheet metallic plates permanently associated with and in fixed flatwise position upon the rear face of said rigid plate, said sheet metallic plates completely covering and permanently closing some of the openings of said rigid plate, and through-bolts engaging with said rigid plate and said sheet metallic plates for permanently securing the same in fixed relation, the marginal portions of said respective sheet metallic plates projecting beyond the edges of the respective openings; substantially as described.

2. The stove or range wall herein described, the same including a relatively heavy, thick, cast-metal rigid plate, said plate being transversely provided within its area with a plurality of separate openings, a plurality of separate independent relatively thin enameled plates, permanently associated with and in fixed flatwise position upon the rear face of said rigid plate, said enameled plates completely covering and permanently closing some of the openings of said rigid plate, and through-bolts engaging with said rigid plate and said enameled plates for permanently securing the same in fixed relation, the marginal portions of said respective enameled plates projecting beyond the edges of the respective openings; substantially as described.

In testimony whereof, I have signed my name to this specification in the presence of two subscribing witnesses.

WILLIAM N. GOLDHAMER.
